UNITED STATES PATENT OFFICE.

ARTHUR F. BAILLY, OF TRENTON, NEW JERSEY.

FOLDING SWING-CHAIR.

1,303,012.

Specification of Letters Patent.

Patented May 6, 1919.

Application filed February 13, 1919. Serial No. 276,752.

To all whom it may concern:

Be it known that I, ARTHUR F. BAILLY, a citizen of the United States, and a resident of Trenton, in the county of Mercer and State of New Jersey, have invented a new and Improved Folding Swing-Chair, of which the following is a full, clear, and exact description.

This invention relates to swinging chairs or like articles of furniture and has particular reference to a folding chair or cot adapted to be adjusted for use in either sitting, reclining or any intermediate stage, being adapted to be folded into very small or flat space for transportation, or storage purposes, and one which is designed to provide a maximum degree of comfort to the occupant and with means for causing the swinging thereof by a simple and convenient foot manipulation independent, however, of the floor or other stationary object.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

Figure 1 is a perspective view of a preferred embodiment of the invention adjusted for use as a swinging chair.

Fig. 2 is a similar view indicating the adjustment of the device as a cot.

Fig. 3 is a front elevation of the device folded, portions being broken away.

Fig. 4 is a similar view on the opposite side from Fig. 3.

Fig. 5 is a plan view of the device in the position of Fig. 3.

Fig. 6 is a horizontal section on the line 6-6 of Fig. 3.

Fig. 7 is a vertical section on the line 7-7 of Fig. 3.

Fig. 8 is a detail sectional view on the line 8-8 of Fig. 6; and

Figs. 9 to 16 are detail views of various connections described more fully below.

Referring now more specifically to the drawings I show a main support comprising two open topped rectangular front and rear frames 20 and 21 pivoted together at

their upper ends by means of two coaxial jointed pivots 22 each comprising screw and socket members 22^a and 22^b respectively fitted in cylindrical holes 23 formed in the upper ends of the frame members and locked therein by means of keys 24. (See Fig. 9). It will be noted that these screw and socket members have no parts projecting beyond the surfaces of the frame members, and yet they provide a strong and reliable pivot means between the parts. Each frame member comprises a horizontal bar or brace 25 having its ends secured to the corner or foot portions of the frame by means of anchor braces 26 preferably countersunk into the frame members or legs and the cross brace as shown in Fig. 16. The cross brace and the anchor members preferably lie flush at the front and rear faces of the frame members, but the braces 25 are approximately only half the width of the frame members from front to rear. The frame members 20 are notched out at just back of the brace 25 to admit the brace of the rear frame members 21 in folded position, (see Figs. 5, 7 and 8) hence no part of the frame members or cross braces extend beyond the thickness of the members 20 and 21 when folded. The frames 20 and 21 constitute a sort of self bracing support for the entire structure and the spread of the frame members from each other is preferably limited by a pair of hooks 28 secured to the rear edges of the frame members 20 and coöperating with holes 29 bored laterally through the companion legs or frame members 21; said hooks 28 in the folded position of the device lie hidden in recesses 30 formed in the frame legs 20.

Attached directly to the main frame support and pivoted coaxially with the pivots 22 thereof is what I term a hanger comprising two pairs of front and rear bars 31 and 32 each pair being pivoted together at their upper ends by screw and socket members 33 and 34 of the same general character as the members 22^a and 22^b above described though of preferably smaller diameter, and the socket member 34 has a laterally projecting screw end fitted into the socket 35 of the screw member 22^a whereby the hanger members are connected coaxially with the pivot members 22 of the main frame. (See Fig. 9). The screw and socket members 33 and 34 are locked in their

respective hanger members by pins 36. The threaded engagement between any one of these pivot members and the adjacent member provides free swinging movement as far 5 as desired without materially loosening or weakening the connection between them, and yet there are no parts projecting from the frame members that would tend to interfere with the close folding or nesting of the 10 parts or endanger the occupant's clothing or person. As indicated in Figs. 3, 4, and 6 the frame and hanger members are all adapted to lie in essentially the same plane or flat space when folded. The members 31 15 and 32 of each pair are adapted to be braced in position with their lower ends spread apart by means of a rod 37 jointed at 38 to the rear edge of the member 31 and having a hook coöperating with any one of a series 20 of holes 39 formed in the lower portion of the other hanger member. These holes, like the holes 29, are bored laterally into the members 32.

The seat or bed portion of the chair or cot 25 comprises a foldable frame and a flexible webbing formed of fabric or its equivalent reaching all the way from the head to the foot portion thereof whereby maximum comfort to the occupant is assured, practically 30 no hard or rigid portions of the chair or cot being subjected to direct contact of the person to his discomfort.

The frame portion of the seat or cot includes a plurality of members arranged in 35 pairs on right and left sides and for convenience in description these members may be termed back members 40, hip members 41, thigh members 42, leg members 43 and foot members 44, each member of each pair being 40 pivoted at at least one end to another member of adjacent pair. More specifically the back members 40 are pivoted at 45 to the hip members 41 while the front ends of the hip members are pivoted at 46 to the lower ends 45 of the hanger members 31. The lower or rear ends of the thigh members 42 are jointed preferably as shown in Fig. 1 in detail to the rear hanger members 32 by means of a double threaded bolt 47 tapped into a pair 50 of bosses 48 rigidly secured as by suitable rivets 49 to the respective members 42 and 43. The length of the threaded bolt 47 thus provides sufficient clearance between the members 42 and 32 to accommodate the hip 55 members 41 and hanger members 31, (see Figs. 3 and 4) and yet the character of the joint as indicated in Fig. 11 possesses ample strength for all practical purposes. The thigh members 42 are jointed to the leg members 43 by means of pivots 50, and the foot members are pivoted to the leg members by means of pivots 51. In comparing Figs. 1 and 2 it will be noted that the inclination of the back members 40 with respect to the hip 60 members 41 around the pivots 45 may be

regulated by means of rods 52 jointed to the rear edges of the rear hanger members 32, (see Fig. 3) and have hooks engageable in any one of a long series of holes 53 bored laterally into the back members 40. Thus 70 the back members may be adjusted if desired through any desired angle from horizontal to vertical. When in folded condition the hooks of the rods 52 are fitted into holes 54 bored in the rear faces of the hanger bars 32 75 and likewise the rods 37 are so folded as to have their hooks project into holes 55 bored in the rear edges of the front hanger bars 31. Thus the pivoted hooks or braces are provided with means to prevent dangling or interference in the folding action. The foot members of the chair frame are provided with a cross bar or toe piece 56 against which the toes may be rested on occupying the chair or cot. The foot piece is maintained in upright position by means of coil spring connections 57, or their equivalent, with the upper ends of the stationary frame members 20 where they are engageable with hooks 58 set into notches 59. (See Figs. 1, 2 and 4). 80 When sitting or reclining upon the chair or cot a slight degree of pressure of the toes upon the toe piece 56 will react through the springs 57 to cause a swinging movement of the entire device except the stationary frame 85 around the axis of the pivots 22.

The head portion at the back comprises a fixed cross rod 60 extending permanently between the back members 40 at a suitable distance below the upper ends thereof and above this bar 60 is arranged a padded head rest 61 mounted to swing around the axis of two pivot members 62 parallel to the rod 60. The head rest comprises a main pillow portion and two auxiliary pads 63 and 64 100 which may occupy various positions according to the position or inclination of the occupant. Compare Figs. 1, 2 and 7. In Fig. 1 the auxiliary pillows 63 and 64 are idle, hanging back of the bar 60. In Fig. 2 both 105 of the auxiliary pillows are folded so as to form an additional head rest on top of or in front of the main head rest 61. The swinging of the head rest 61 accommodates this multiple head rest device to its different positions. Obviously in the folded position of the chair or cot the several portions of the head rest are laid out as flat as possible.

The main body support as above intimated 110 comprises a flexible sheet or strip of any suitable fabric 65, the head end of which is fixed permanently to the cross bar 60 while the remaining portion thereof is projected downward and forward to a roller 66 at the occupant's heels. Any suitable ratchet 115 mechanism or the like may be provided to prevent undesired loosening of the webbing by the rolling of the roller 66. The only intermediate supports for the webbing 65 are a plurality of transverse flexible and prefer- 120

ably elastic straps 67 and 68 under the back and legs of the occupant respectively. The back strap 67 is attached to the lower ends of the back members 40 and the leg strap 68 is attached to the front ends of the thigh members 42. I thus provide an exceedingly comfortable bed or seat for the occupant, the webbing 65 conforming automatically to the person's figure. The straps 67 and 68 are permanently attached in the places indicated, interfering in no way with the folding of the device.

Referring now to Figs. 2, 13, 14 and 15 I provide peculiar arm rests and joints for the same, each arm rest including an arm rest proper 69 comprising a rigid bar of wood or the like having interlocking jointed connection with a back frame bar 40 through devices shown in the detail views and comprising a bracket 70 countersunk into the front face of a bar 40 and having a finger 71 projecting inward toward the opposite arm rest, the axis of the finger being approximately opposite the middle portion of the bar 40. The bracket includes also between the finger and bar a pair of teeth 72 projecting forward. The rear end of the arm rest 69 carries a rigid bracket 73 having loose pivotal connection through a slot 74 with the finger 71 and having adjacent to the slot portion a series of teeth 75 arranged in an arc of a circle for direct interlocking coaction with the teeth 72. The main portion of the bracket 73 is angular so as to present a flat face 76 against the front face of the back member 40 making a substantially rigid arm rest after it is adjusted. The variation in radius between the finger 71 and the contacting portion of the arm rest is compensated for by the slot 74. Compare Figs. 14 and 15. Obviously, however, the arm rest may be set at any angle and provided for by the interlocking teeth 72 and 75. In the folding of the device each arm rest is simply slipped laterally along the finger 71 so as to clear the bar 40 and its bracket 70 and yet retain pivotal engagement between the two brackets.

Supplemental to the transverse bracing means for the frame members I provide a bar 77 extending across between the rear ends of the hip members 41 as a permanent connection and fixed thereto within cutaway parts 78. When the device is folded the back members 40 fold against the rear face of the cross bar 77. Another bar 77' extends across between the front ends of the hip members 41. Attention is called also to a pair of legs 79 pivoted upon the cross rod 60 and lying against the inner faces of the back members 40 when the device is folded, which may or may not be used according to whether the swinging arm is desired to be held stationary or allowed to swing freely.

I claim:

1. In a swinging chair, the combination of a main support, a hanger pivoted to swing within the support, a chair frame comprising a plurality of relatively adjustable members arranged in pairs and connected to the hanger for swinging therewith, a flexible body support adjustable for use as a chair or as a cot and having adjustable connection with the chair frame, and means extending between the chair frame and the main support to cause the swinging of the hanger and chair frame by operation of a portion of the occupant's person.

2. In a swinging chair, the combination of a chair frame, means to suspend the same for swinging movement, said frame comprising pairs of connected members and means to adjust the same into different positions according to the inclination of the occupant, said frame including a foot piece against a portion of which the occupant's feet may bear, a flexible body support connected to and supported by the frame and conforming to the occupant's body, and elastic means extending between the foot piece and the main support whereby the pressure of the occupant's feet against the foot piece will cause the swinging of the chair.

3. In a swinging chair, the combination of a chair frame comprising jointed and foldable members arranged in pairs on opposite sides thereof, a flexible body support extending along the frame from the head thereof to the foot, resilient transverse members extending beneath the back and leg portions of the body support, and an adjustable head rest swung between the head portions of the frame at the upper end of the body support, a portion of the head rest being projectable between the main portion thereof and the body support or into a position on top of the same.

4. In a folding chair, the combination of a plurality of frame members and means pivotally connecting said members together, said means comprising a pair of coaxial screw and socket members fitted within the surfaces of the frame members, one of the frame members being provided with a screw threaded into the socket members, and means to lock said members in the frame members set forth.

5. In a swinging chair, the combination of a pair of relatively stationary frame members, a pair of screw and socket members fitted in the respective frame members and having rotatable connection with each other, a pair of swinging frame members adjacent to the stationary frame members, and pivot connections between the swinging frame members and the stationary frame members all arranged coaxially of one another.

6. In a folding swing chair, the combina-

tion of a relatively stationary support, a hanger comprising two bars, pivot connections between the two hanger bars and the first mentioned frame, and pivot connections between the remote end of one of the hanger bars and one of the supporting frame bars and pivot connections between the other hanger bar and the other supporting frame bar, the two members connected by the last

mentioned connections lying in close relation to each other and between the previously mentioned hanger bar and supporting frame member, the pivot connections for the first mentioned hanger bar and frame member providing for the folding of the other members between them. 10 15

ARTHUR F. BAILLY.

Copies of this patent may be obtained for five cents each, by addressing the "Commissioner of Patents, Washington, D. C."
